A. E. CROUCH,

RAIL JOINT

APPLICATION FILED OCT. 5, 1917, RENEWED JUNE 7, 1920.

UNITED STATES PATENT OFFICE.

ALVA E. CROUCH, OF CLOVERPORT, KENTUCKY.

RAIL-JOINT.

1,366,248.

Specification of Letters Patent. Patented Jan. 18, 1921.

Application filed October 5, 1917, Serial No. 194,938. Renewed June 7, 1920. Serial No. 387,243.

To all whom it may concern:

Be it known that I, ALVA E. CROUCH, a citizen of the United States, residing at Cloverport, in the county of Hancock and State of Kentucky, have invented certain useful Improvements in Rail-Joints, of which the following is a specification, reference being had therein to the accompanying drawing.

- 10 The present invention has reference generally to improvements in that class of inventions known as railway rails and rail joints and more particularly relates to an improved rail joint.
- 15 It is the primary aim and object of this invention to provide a device of the above character wherein the meeting ends of a pair of rail sections are supported in abutting relation with respect to each other while the 20 fastening means of the sections is locked against displacement.

As an equally important object this invention contemplates the provision of a rail joint designed to engage and support both 25 the rail sections and the angle plates fastened to the rail sections and forming a part of the joints.

More particularly this invention embraces the provision of a rail joint wherein means 30 is cast with the bridging base preferably near the respective ends thereof for coöperating with the base in effectively maintaining the rail sections and angle bars in the bridging base so that they may be sup- 35 ported.

Among the other aims and objects of this invention may be recited the provision of a device of the character mentioned with a view to compactness, and in which the parts 40 are few, the construction simple, the cost of production low and the efficiency high.

Other improvements and novel details in the construction and arrangement of the various parts of the apparatus will be brought out more in detail in the description 45 to follow, which for a clear understanding of the invention, should be considered in connection with the accompanying drawings forming a part hereof and wherein is disclosed for the purpose of illustration a convenient and satisfactory embodiment of the invention. It is to be noted in this connection that minor changes in the construction and arrangement of parts may be made 50 without departing from the spirit of the in-

vention or the principle of operation of the various parts.

The invention is clearly illustrated in the accompanying drawings in which:

- Figure 1 is a side elevation thereof; 60
Fig. 2 is a transverse section taken on line 2—2 of Fig. 1;
Fig. 3 is another transverse section taken on line 3—3 of Fig. 1;
Fig. 4 is a horizontal section taken on line 65 4—4 of Fig. 1 looking in the direction in which the arrows point; and
Fig. 5 is a perspective detail of the bridging base or supports.

Similar characters of reference indicate 70 corresponding parts throughout the several views in the drawings.

Referring now, more particularly, to the accompanying drawings there are provided a pair of rail sections 1 and 2 the meeting 75 ends of which are held in abutting and alining relation with respect to each other on the track bed by means of the improved rail joint designated in its entirety by the numeral 3. 80

In fastening the sections in alining relation, angle plates indicated in their entireties by the numeral 4 are employed and positioned upon the respective sides of the web and base portion of the rail sections. Each 85 angle bar consists of a vertical web engaging portion 5 the upper edge of which contacts with the under surface of the heads of the rail sections at the meeting ends and an outwardly projecting rail base flange engag- 90 portion 6 which terminates beyond the side edge of the adjacent base portions of the rail sections but in a plane above the plane of the lower surfaces of the base portions as indicated in Figs. 2 and 3 for a 95 purpose that will presently appear. Suitable fastening devices such as bolts 9 are extended alternately through alining or registering openings in the vertical web portions 5 and in the web portions of the rail sections 100 1 and 2, the outer ends thereof being engaged by nuts 10 which are desirably of an angular shape and coöperate with the heads of the bolts in effectively clamping the parts in a substantially rigid position so as to 105 maintain the rail sections in abutting and alining relation with respect to each other.

Coöperating with the angle bars and the fastening means is the improved bridging support indicated in its entirety by the nu- 110

meral 11 and preferably cast in a single piece. In the present instance this support consists of a base 12 from the upper surface of which and longitudinally thereof extend 5 opposed vertical portions 13 while extending inwardly from the upper ends of the vertical portions are the horizontal portions 14 designed for engagement with the upper surfaces of the base engaging portions 6 of 10 the angle bars which engagement is effected subsequent to fastening of the angle bars by sliding the support to engage the angle bars as will be appreciated and when in such position the upper surfaces of the horizontal 15 portions are designed for snug engagement with the adjacent lower surfaces of the nuts 10 so as to lock the nuts against retrograde movement.

The sides or vertical portions 13 are 20 thickened and frictionally and snugly engage the sides of the base portions of the rail sections when the support is arranged in an operative position and in addition are provided with the longitudinal grooves 17 25 in which are snugly and frictionally received and supported the projecting edges of the flange engaging portions 6.

Horizontal flanges 18 extend outwardly from opposite sides of the base 12 and are 30 provided with openings and notches 19 for receiving spikes or like fastening devices 20 which are adapted to be anchored in ties for effectively maintaining the parts in their 35 assembled position as described and as indicated in the drawing.

It is believed in view of the foregoing description that a detailed description of the operation of the invention is entirely unnecessary. Likewise it is believed that 40 the advantages of the invention will be readily apparent.

As many changes could be made in the above construction and many apparently widely different embodiments of this invention 45 could be made without departing from

the scope thereof, it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope of the invention, which, as a matter of language might be said to fall therebetween.

What is claimed is:

The combination with the meeting ends of a pair of rail sections, of angle bars disposed on opposite sides of the rail sections 60 at the meeting ends thereof and including vertical web engaging portions, and base engaging portions the outer sides of which project slightly beyond the side edges of the bases of the rail sections, means for fastening the web portions to the rail sections so as to hold the rail sections in alinement and abutting relation, a bridging support for slidably engaging with the rail sections and the angle plates for preventing sagging of the sections, for preventing accidental displacement of the fastening means, said support including a base, thick vertical side portions integral with the upper surface thereof and designed to snugly and frictionally engage the side edges of the base of the rail sections, inwardly extending horizontal flanges for engagement with the base engaging portions of the angle bars, the inner faces of the vertical portions being 65 provided with opposed longitudinal grooves immediately above the horizontal flanges for snugly and frictionally receiving the outer projecting side edges of the base engaging portions of the angle bars, the outer 70 ends of the vertical portions being tapered 75 inwardly to form guides and means for securing the support in position.

In testimony whereof I affix my signature.

ALVA E. CROUCH.
